UNITED STATES PATENT OFFICE.

THOMAS HENRY WARD, OF TIPTON, COUNTY OF STAFFORD, ENGLAND.

PULLEY-BLOCK.

SPECIFICATION forming part of Letters Patent No. 267,954, dated November 21, 1882.

Application filed July 3, 1882. (No model.) Patented in England December 5, 1881, No. 5,311.

To all whom it may concern:

Be it known that I, THOMAS HENRY WARD, (of the firm of HOWL, WARD & HOWL,) a subject of the Queen of Great Britain and Ireland, 5 and residing at Tipton, in the county of Stafford, England, have invented certain Improvements in Pulley-Blocks, parts of which improvements are also applicable to cranes, overhead travelers, hoists, and other like receptacles, (for which I have obtained a patent in 10 Great Britain, No. 5,311, dated 5th December, 1881,) of which the following is a specification.

My invention relates to improvements in differential pulley-blocks of the description known 15 as "Weston's," parts of which are also applicable to certain other kinds of pulley-blocks, and has reference partly to a former invention for which British Letters Patent were granted to myself and Edmund Howl, dated the 17th 20 September, 1881, No. 4,012, in that the subject-matter of that patent may be used in combination with pulley-blocks provided with my present improvements.

According to one part of my present invention, which applies to Weston's pulley-blocks, I invert the arrangement of the said blocks—that is to say, I place the single sheave at the top and the differential sheaves at the bottom. It will be seen, therefore, that the single sheave 30 will form the fulcrum, and that the differential sheaves will rise and fall as a Weston's bottom sheave. I guide the chain, after it has passed over the top sheave and partly round one of the differential sheaves, down the opposite side and up again onto the other differential sheave by means of guide-wheels, or, what is equally as well, down and up guide-pieces, and allow it to hang loosely near the ground, as a loop forming an endless chain. It 40 will be seen that this loop remains in the same position—that is, the chain itself will neither rise nor fall bodily, and also that there are two lines only of chain, instead of four lines of chain, having two loops rising and falling, and that there is thus less liability of the chain becoming 45 entangled. The block may be operated from the chain direct, or by rotating the top sheave or the bottom sheaves by means of a sprocket-wheel or ratchet-lever, or equivalent devices.

Figure 1 of the accompanying drawings rep-

resents in side elevation, and Fig. 2 in transverse vertical section, a pulley-block constructed or arranged according to my invention.

The single sheave at top is marked A, and 55 its suspending-shackle is marked *a*. The differential sheaves at bottom are marked B and C, and the shackle for suspending the load is marked *d*. In Fig. 1 the differential sheaves are shown in section, one-half of the section 60 being taken on a line through the one sheave and the other half through the other sheave. The chain *E* is passed partly around the one sheave of the differential sheaves, then over the upper sheave, A, and partly around the 65 other sheave of the differential sheaves. The said chain, at the part which forms the loop extending below the bottom sheaves, is guided so as to keep the chain in gear with the sheaves by means either of rollers or guiding-surfaces. 70 In the drawings I have shown guiding-surfaces as being employed. They consist of two curved horn-pieces, *f*, carried by the cross-piece *d*² of the lower shackle, *d*. These guiding-pieces are shown separately drawn to a larger scale in 75 side view and plan, respectively, in Figs. 3 and 4. The cross-pins *f*² are to prevent the chain *E* from getting out of place. It will be seen that rollers can take the place of the guides *f*, if desired, and that by this arrangement of the 80 pulley-block the chain *E* is not liable to become entangled, and that a large saving is made in the quantity of such chain required.

Another part of my invention relates to the gearing of blocks in order to obtain greater 85 purchase.

In lieu of driving the differential sheaves by means of inside or outside spur-gear, I drive them by means of endless-chain gear. For this purpose there is cast in one or more sheaves 90 underneath the toothed bed or groove for the main chain another toothed bed or groove for receiving a much smaller endless chain. This chain, after passing around this additional bed or groove, passes over a corresponding chain-pinion situate between the two lines of loaded chain, to which pinion the power is applied. This part of my invention is illustrated as applied to two sheaves in Figs. 1 and 2 of the drawings. The sheaves B and C have their 95 main chain beds or grooves deepened at *g*, so as to form additional beds or grooves with

teeth to constitute chain-pulleys to receive small driving-chains *h*, passing thereover and over corresponding toothed grooves in the chain-pinion *i*, carried in the upper part of the 5 lower-sheave framings, as shown. The driving of the pinion may be effected in any convenient manner. In Fig. 2 there is shown for this purpose a ratchet-wheel, *j*, attached to the axis of the pinion *i*, the lever *k* and pawl 10 *k'* being actuated like a ratchet-brace to rotate the pinion *i*, and through it and the chains *h* the sheaves of the pulley. If desirable, however, this chain-gear may be situate in a like manner in the bed of the single sheave above 15 and then be actuated, as described, or it may be applied for driving the top sheaves of an ordinary Weston block.

Fig. 5 represents in elevation, and Fig. 6 in vertical section, a Weston block provided 20 with the said improvement. The parts which correspond with those shown in Fig. 2 are marked with the same letters of reference, and as the arrangement of my improvements in this respect is essentially similar to the arrangement of the improvements as shown in 25 the said Fig. 2, these Figs. 5 and 6 call for no further description. I have here shown a sprocket-wheel, *l*, as the means for giving motion to the pinion *i*, which in this arrangement 30 is of course situated beneath the sheaves *B* and *C*. It is evident, therefore, that the same gear is applicable, whether the differential sheaves be situate above, as in a Weston block, or below, as in the arrangement hereinbefore first 35 described, or whether one or more of the differential sheaves or the single sheave be driven.

The chains *h* will have a strain upon them in a proportion varying with the load; but this strain will of course be of much smaller amount 40 than that on the main chain. I prefer for safety's sake to make the said chains *h* weaker in proportion than the main chain, so that these chains will break before the main chain, and thus prevent injury should the apparatus be 45 unduly strained. This chain-gear may be com-

bined with the lowering-gear described in the specification filed by myself and the said Edmund Howl, in pursuance of the before-mentioned Letters Patent dated the 17th September, 1881, No. 4,012, by arranging the block as 50 a non-self-sustained block and introducing the detent and ratchet-wheel in the manner described in the said specification. This lowering-gear is shown at *x* in Figs. 1, 2, and 5, 6, 55 and as its application differs in no respect from its application as described in the said prior specification it calls for no further description.

My invention is also applicable to cranes, overhead travelers, hoists, and other like apparatus to which it is or may be applicable. 60

Having now described and particularly ascertained the nature of my said invention and the manner in which the same is or may be used or carried into effect, I would observe, in conclusion, that what I consider to be novel 65 and original, and therefore claim, is—

1. A pulley-block having the single sheave at the top, and the differential sheaves below, with a chain passing over said single sheave and partly around said differential sheaves, and 70 guides for crossing said chain into a loop below the latter, all substantially as described.

2. The combination of the upper sheave and chain and the lower differential sheaves with the crossed-chain guides *ff* below the latter, 75 substantially as set forth.

3: The combination of sheaves having two sets of grooves, one within the other, with two sets of chains and an actuating-shaft having a driving pinion or pinions for the inner chain, 80 substantially as specified.

In testimony whereof I have signed my name to this specification in the presence of two subscribing witnesses.

THOMAS HENRY WARD.
